James C. Ledbetter

UNITED STATES PATENT OFFICE.

PETER EDUARD GELDHOF, OF SYRACUSE, NEW YORK, ASSIGNOR, BY MESNE ASSIGNMENTS, TO THE NEW YORK TRUST COMPANY, TRUSTEE, A CORPORATION OF NEW YORK.

PRESSURE COMPENSATOR FOR PRESSES.

Application filed October 6, 1920, Serial No. 415,104. Renewed July 24, 1924.

To all whom it may concern:

Be it known that I, PETER EDUARD GELDHOF, a citizen of the United States, residing at Syracuse, in the county of Onondaga and State of New York, have invented certain new and useful Improvements in Pressure Compensators for Presses, of which the following is a specification.

This invention relates to presses and kindred machinery, and more particularly to an improved pressure compensator for garment presses.

Among the several objects of this invention, a primary one is to produce a pressure compensating device used in connection with all types of garment pressing machinery for transmitting an even, firm yet slightly yielding pressure from the prime mover to the part moved as for example the press head working against the garment on the buck.

Some garment presses are subjected to usages of a varying nature and in fact rough usage when pressing garments of various thicknesses and when worked by inexperienced operators. The device constituting this invention establishes uniform and even pressure between the pressing elements and the garment; and furthermore eliminates all possible breakages of the press lever or other parts when the press is driven abnormally hard against a thick garment, without proper adjustment, as may possibly happen when the press is operated by an inexperienced or careless hand.

The accompanying drawings form a part of these Letters Patent, and Figure 1 illustrates a side elevation of a typical garment press embodying a pressure compensator. Figure 2 illustrates a longitudinal sectional view of the pressure compensator.

Referring still further to the drawings for a more complete description of the invention, there is shown a press frame 4, on the upper part of which is fulcrumed a press lever 5. The frame supports the usual garment supporting buck 6, and the lever 5 carries the usual pressing head 7, either or both of which are provided with steam for heating and treating purposes as is known to those conversant with the art.

A foot lever 9 is pivoted in the lower portion of the frame and connects through a link 10 with a toggle comprising the pivotally joined parts 11 and 12. The toggle 11-12 has one end thereof pivotally con-

nected with the press frame, and the other end is connected to the lower part 14 of the toggle 14-15. This vertical toggle 14-15 is pivotally connected to the back end of the press lever 5 and has its lower end pivotally supported on the pin 16 which may be either fixed to the press frame or to a power part 17 as the case may be.

The press lever 5 and pressing head 7 are actuated by manually depressing the foot lever 9, and a spring 19 is attached to the toggle 14-15 and to the frame 4 to normally hold the vertical toggle in a broken position so as to restrain the press head 7 in open position in order that a garment may be quickly placed on the buck 6 and made ready for pressing.

The foregoing description covers generally the organization of some of the machine parts employed in a typical garment press, and the present invention has to do more particularly with one member or part 15 of the main press toggle 14-15, which has been above referred to as a compensator, a description of which will now be given.

A spring cup or base 15 is provided with depending spaced parallel ears 24 with a hole therethru providing for a pin 25 to attach the lower end of the compensator device to the upper end of the toggle part 14. The spring cup is flanged as pointed out at 26 and a threaded bore 27 made centrally through this base part.

The larger end 27 of an adjusting stem is threaded and screwed into the base 15. A heavy spring 28 rests against the base 15 and is confined in position by the flange 26. A spring cap 29 is placed on top of the spring 28.

A pressure block 31 is made with an integral sleeve 32 and rests upon the spring cap 29 with the sleeve 32 projecting downwardly part way through the spring 28. The pressure block 31 has an opening made therethrough for the reception of the upper smaller end 33 of the adjusting stem which renders the stem and pressure block adjustable or movable one upon the other. The pressure block has a hole 37 for the reception of a pin 38 employed in assembling the compensator device within the press lever 5.

The adjusting stem projects from the pressure block 31 and has an adjusting nut 35 fixed to the stem by taper pins or other

suitable means so that a wrench may be applied to the nut to turn the screw 27 to screw this part farther into the base 15. Several adjusting screws 36 are screwed into the pressure block 31 and engage the face of the spring cap. These adjusting screws 36, preferably about three in number, are equidistantly disposed about the stem 33 so as to uniformly transmit the pressure delivered from the spring to the pressure block.

When the pressure compensator 15 is installed within the press lever 5 and has its lever end attached to the toggle part 14, as hereinbefore described, why then, the pressure compensator itself acting with the part 14 constitutes the main toggle of the press; and when the foot lever or pedal 9 is thrust downwardly the toggle 14-15 straightens to jam the head 7 against the buck 6. In executing this pressing action, the lateral force developed in the toggle 11-12 straightens the vertical toggle 14-15, whereupon the thrust is translated into a vertical force exerted through the straightened vertical toggle, and against the back end of the press lever 5.

The force working against the press lever to close the head 7 is transmitted from the base 15 through the spring 28 to the spring cap 29 and then through the adjusting screws 36 to the pressure block 31 and finally delivered against the press lever 5. Now in case the toggle part 15 was of the rigid or non-yielding type, there would be considerable danger of breaking some part of the press. But by employing the yieldable yet very stiff and firm spring 28, the danger of breakages is eliminated without impairing the pressing capabilities of the machine.

At times a press is put to unusual hard tasks in pressing very thick and heavy goods and in such cases the distance between the points 38 and 16 on the press must be adjusted or shortened up so that the vertical toggle will straighten by the time the head closes on the garment. This is accomplished by rotating the stem 27 to draw the pressure block and base closely together; and when this adjustment is made it is usually practical to loosen up on the spring 28 by unscrewing the adjusting screws 36 to relieve slightly the increased pressure of spring 28.

Again it is often necessary to slightly vary the pressure between the pressing elements 6 and 7 in the treatment of various kinds of fabrics; and less pressure or more pressure as desired, may be obtained by the proper adjustment of the screws 36 to vary the compression of the spring 28.

Having thus described the construction and operation of the invention, what I de-

sire to secure and obtain by Letters Patent is:

1. A pressure compensator constructed as a part of a toggle used to swing a press lever, comprising a base attachable to a toggle part; a pressure block attachable to the aforesaid press lever; an adjustable stem threaded into one of the aforesaid parts to vary the distance between the base and block; a compression spring bearing at one end on the base; a cap bearing on the opposite end of the spring; and adjusting screws mounted in the pressure block and bearing against the cap to vary the compression of the spring.

2. A pressure compensator for presses comprising a pressure block with a bearing hole to pivotally mount the block on a press part, said block having another bearing hole formed longitudinally therethru and passing at right angles thru the first named bearing hole, a spring base, a spring confined between the base and block, a spring cap disposed between the block and spring end, spring adjusting screws cooperating with the block and cap to increase or decrease the spring compression, and an adjusting screw cooperating with the block and base to vary the overall length of the compensator and rotatably confined within the second bearing hole.

3. A pressure compensator for presses comprising a pressure block, a sleeve formed thereon, a spring base, a compression spring disposed on the sleeve and having one end supported on the spring base, a spring cap slidably confined on the sleeve and bearing against the other end of the spring, a screw means for adjusting the position of the spring cap in relation to the block to adjust the spring compression, and an adjusting stem guided in the sleeve and connected with the spring base and block to vary the overall length of the compensator.

4. A pressure compensator and equalizer comprising a block, two independent screw adjusting means carried in the block with heads or nuts conveniently located above the block to render the means accessible, a spring base carried on one end of the said screw means and spaced from the block in an adjustable manner whereby the screw is useful in shortening or lengthening the compensator, a spring confined between the base and block, and a spring cap resting on one end of the spring and movable up and down against the spring under the action of the other screw means to adjust the spring compression.

In testimony whereof I hereunto affix my name this 1st day of October, 1920.

P. EDUARD GELDHOF.
